(57) **CLAIM**

The ornamental design for an optical type sorter, as shown and described.

DESCRIPTION

FIG. 1 is a perspective view of an optical type sorter showing the new design;
 FIG. 2 is a front view thereof;
 FIG. 3 is a rear view thereof;
 FIG. 4 is a left side view thereof;
 FIG. 5 is a right side view thereof;
 FIG. 6 is a top plan view thereof; and,
 FIG. 7 is a bottom plan view thereof.
 The broken lines are for illustrative purposes only and form no part of the claimed design.
